Inventor,

William L. Paine

United States Patent Office.

WILLIAM L. PAINE, OF BOSTON, MASSACHUSETTS.

Letters Patent No. 70,887, dated November 12, 1867.

IMPROVED CARD-HOLDER FOR TRUNKS.

The Schedule referred to in these Letters Patent and making part of the same.

TO ALL WHOM IT MAY CONCERN:

Be it known that I, WILLIAM L. PAINE, of Boston, in the county of Suffolk, and State of Massachusetts, have invented an Improved Card-Holder for Trunks, of which the following is a full, clear, and exact description, reference being had to the accompanying drawings, making part of this specification, in which—

Figure 1 is a perspective view of my improved card-holder.

Figure 2 is a section on the line xx of fig. 1.

Figure 3 is a section on the line yy of fig. 1.

This invention has for its object to provide a ready means of attaching address-cards to trunks, and consists in two plates, secured at a suitable distance apart, and having sufficient spring to allow the ends of the card to be inserted beneath them, the card being held securely in place by suitable projections or points.

To enable others skilled in the art to understand and use my invention, I will proceed to describe the manner in which I have carried it out.

In the said drawings, A represents the side of a trunk, to which are attached, at a suitable distance apart, by means of the screws a , two narrow strips or plates, B C, of thin metal, which possess sufficient spring to allow their inner edges 4 to be raised by the fingers, in order to insert the extremities of a card, D, bearing the required address, which is held securely in position by means of sharp points b , projecting from the under side of the plates B C, which pass through the ends of the card into recesses c made to receive them.

If preferred, the points which serve to hold the ends of the card D may be made to project out from the side of the trunk beneath the plates B C, instead of from the plates themselves, as above described, without departing from the spirit of my invention, and any desired number of points or projections may be used.

The length of the strips B C should be sufficient to admit the ends of a card of considerable width, and if the card should be longer than the distance between the strips, its ends will project out beyond them, as seen in red in fig. 1.

When it is desired to remove the card, it is merely necessary to raise the edges 4 of the plates B C, so as to withdraw the points b from the card, which is then free to be drawn out.

The above-described card-holder is of simple construction, and can be furnished at a trifling cost, while by its use a card of any ordinary dimensions, bearing the desired address, may be readily attached to a trunk, and held securely in place, thus avoiding the necessity of driving tacks into the sides or top of a trunk, which would mar and deface it.

Claim.

What I claim as my invention, and desire to secure by Letters Patent, is—

The within-described card-holder for trunks, consisting of the strips or plates B C, in combination with points or projections, or their equivalent, for holding the card securely in place, substantially as set forth

WILLIAM L. PAINE.
